UNITED STATES PATENT OFFICE.

WILLIAM W. McMURTRY, OF NEW CASTLE, PENNSYLVANIA.

MORTISING-MACHINE.

1,090,323.

Specification of Letters Patent. Patented Mar. 17, 1914.

Application filed July 8, 1912. Serial No. 708,299.

To all whom it may concern:

Be it known that I, WILLIAM W. McMURTRY, a citizen of the United States, residing at New Castle, in the county of Lawrence 5 and State of Pennsylvania, have invented a new and useful Mortising-Machine, of which the following is a specification.

One object of the present invention is to provide an attachment which may be assembled readily with the shaft of a boring 10 machine of any standard construction, for the purpose of cutting a rectangular hole in the material.

Another object of the invention is to provide a carrying member of novel form, adapted to support the mortising chisel, and adapted to be rotatably mounted upon the shaft of the boring machine, means being provided for holding the carrying member 20 against rotation, and for rotating the carrying member to position the opening properly with respect to the work.

The invention aims to provide novel means for assembling the carrying member 25 with the shaft of the boring machine, and to provide novel means for assembling the mortising chisel with the carrying member.

With the foregoing and other objects in view, which will appear as the description 30 proceeds, the invention resides in the combination and arrangement of parts and in the details of construction hereinafter described and claimed, it being understood that changes in the precise embodiment of invention herein disclosed can be made within 35 the scope of what is claimed without departing from the spirit of the invention.

In the drawings,—Figure 1 shows in side elevation, the device constituting the subject-matter of the present invention assembled 40 with a boring machine; Fig. 2 is a side elevation of the carrying member and attendant parts; and Fig. 3 is a longitudinal vertical section of the structure shown in Fig. 2.

45 In the drawings, and referring particularly to Fig. 1, there is shown a boring machine which will be described briefly, it being understood that the device herein disclosed, is adapted to be assembled in boring 50 machines of widely different forms.

The specific form of boring machine shown in the drawings comprises a supporting post 1, carrying a vertically adjustable work table 2. A bracket 3 is secured to the 55 support 1, the bracket terminating at one end in a vertical bearing 4 in which the bor-

ing shaft 5 of the machine is journaled for rotation. The upper end of the boring shaft 5 is journaled in a yoke 6, but is held against longitudinal movement in the yoke, the yoke 60 being pivotally connected with a lever 7, fulcrumed upon a link 8 supported by the bracket 3, the lever 7 carrying a counter-weight 9. A standard 10 is slidable in a socket 11 which is pivoted to the lever 7, 65 the lower end of the standard 10 being secured to the upper end of the bearing 4, a stop 12 being adjustable along the standard 10, for the purpose of limiting the downward swinging movement of the free end of the 70 lever 7. Depending from one end of the lever 7 is an actuating member 14.

The means for imparting rotation to the shaft 5 is shown in the present instance as comprising a friction disk 15 which is secured to the shaft 5 below the bearing 4, 75 the friction disk being engageable by a friction wheel 16 secured to a shaft 17 journaled in the bracket 3, any suitable means 18 being provided for operatively connecting the 80 shaft 17 with a prime mover. A collar 19 is clamped upon the shaft 5 below the friction wheel 15, the collar ordinarily consisting of a pair of slidably interlocking members 20, provided with set screws 21 adapted 85 to engage the shaft 5.

The invention includes a carrying member which is denoted generally by the numeral 22, the carrying member including an upper or primary head 23, a lower or 90 secondary head 24, and downwardly converging, oppositely disposed arms 25, uniting the heads. In the upper face of the head 23 there is a conical recess 24, adapted to receive the tapered lower end 27 of the 95 collar 19. In the lower face of the head 23 there is a conical recess 28, adapted to receive the tapered upper end 29 of a collar 30 which may comprise a pair of coöperating members 31 held together by a clamp 100 screw 32. From the foregoing it will be evident that the collars 22 and 30 prevent the carrying member 22 from moving longitudinally upon the shaft 5, without interfering with the rotation of the carrying 105 member upon the shaft.

A rectangular mortising chisel 33 is provided, the same having a shank 34 which is inserted into the lower head 24 of the carrying member 22, the chisel being held in place 110 in the carrying member by means of a set screw 36, the chisel being equipped with a

laterally projecting shoulder 35, adapted to engage the lower end face of the head 24. A boring bit 37 is secured in the lower end of the shaft 5 by means of a set screw 38, 5 the bit passing through the axis of the mortising chisel 33. In one or more of the side faces of the mortising chisel 33 there are longitudinal openings 41, through which the chips are discharged. In the upper head 10 23 of the carrying member 22 there is a transverse opening 39, into which is threaded, or removably secured in any other desired manner, a laterally projecting bar 40.

The collars 19 and 30, it is to be noted, 15 are rotatably received at their inner ends, respectively, in the recesses 24 and 28, and thus, the collars constitute means for centering the bit 37 in the mortising chisel 33. The collars, further, constitute the sole 20 means for supporting the carrying member upon the shaft, and it is to be noted that the carrying member may be adjusted longitudinally of the shaft, by moving and resetting the collars. Further, the collars 25 afford broad bearing areas. The bit-receiving end of the shaft is of the same diameter as the body portion of the shaft, and thus the upper or primary head 23 may be slipped in place around the lower end of the shaft. 30 The structure herein disclosed may be mounted easily upon the shaft of a boring machine of standard construction, thereby converting the boring machine readily into a mortising machine, without effecting any 35 change either in the bit of the boring machine or in the frame work thereof.

In practical operation, the lever 7 is tilted by means of the actuating member 14 until the lower end of the mortising chisel is 40 brought into close proximity to the work, the carrying member 22 being rotated manually by means of the bar 40, until the cutting end of the chisel 33 is positioned properly with respect to the work, whereupon the 45 chisel is thrust against the work, the bar 40

being held in order to prevent the carrying member 22 and the chisel 33 from rotating. Presupposing that the specific form of driving mechanism shown, is employed, it will be seen that when the shaft 7 is rotated, the 50 friction wheel 16 will rotate the disk 15, the disk 15 rotating the shaft 5 and the shaft 5 rotating the bit 37. The bit 37 will be urged into the work by the action of the lever 7 and, at the same time, the cutting edges of 55 the mortising chisel 33 will be carried downwardly into the work, cutting into rectangular form, the circular opening fashioned by the bit 33.

Having thus described the invention, what 60 is claimed is:—

In a device of the class described, a carrying member comprising primary and secondary heads, and a connection between the heads, the primary head having an opening 65 and being provided in its ends with recesses concentric with the opening; a mortising chisel mounted in the secondary head and disposed concentrically with respect to the opening in the primary head; a shaft located in the opening in the primary head and a bit held in the end of the shaft and projecting into the chisel, the bit-receiving end of the shaft being of the same diameter 70 as the body portion of the shaft, whereby 75 the primary head may be slid onto the bit-receiving end of the shaft; clamping collars detachably secured to the shaft and journaled in the recesses of the primary head, thereby to center the bit in the chisel, 80 the collars constituting the sole means for supporting the carrying member on the shaft, and serving to afford bearing areas.

In testimony that I claim the foregoing as my own, I have hereto affixed my signature in the presence of two witnesses.

WILLIAM W. McMURTRY.
